UNITED STATES PATENT OFFICE.

SAMUEL M. VAUCLAIN, OF ROSEMONT, PENNSYLVANIA. ASSIGNOR TO THE BALDWIN LOCOMOTIVE WORKS, OF PHILADELPHIA, PENNSYLVANIA, A CORPORATION OF PENNSYLVANIA.

TRIPLE-EXPANSION MALLET LOCOMOTIVE.

Application filed November 25, 1925. Serial No. 71,406.

One object of my invention is to construct a triple expansion locomotive of the Mallet type, in which the boiler is rigidly secured to the frame on which are mounted 5 the intermediate cylinders.

A further object of the invention is to support the high-pressure cylinders on the frame of the tender of the locomotive.

In the accompanying drawings:

10 Fig. 1 is a side view of a Mallet triple expansion locomotive illustrating my invention; and

15 Figs. 2^a, 2^b and 2^c are enlarged views constituting a side elevation of the locomotive showing the details of construction.

Referring to Fig. 1 of the drawings, 1 is the boiler, which is rigidly secured to the frame 2 of the locomotive. This frame 2 also carries the intermediate cylinders 3, 20 the saddle 4 of which is secured to the boiler, as shown in Fig. 1, and in detail in Fig. 2^b.

The forward end of the boiler overhangs the forward frame 6, which is connected to 25 the frame 2 by an articulated joint 7 of ordinary construction. Bearing-blocks 8 on the boiler are arranged to slide on the supporting pedestal 9 of the frame. The high-pressure cylinders 10 are carried by 30 the frame 11 of the tender 12, and the tender-frame 11 is connected to the rear end of the frame 2 by an articulated joint 13, so that there are three frames which support the boiler and the tender.

35 On each frame are boxes for the axles 14, 14^a and 14^b, on which are mounted the driving-wheels 15, 15^a and 15^b. The wheels of each frame are connected by rods and to the piston-rods in the ordinary manner. 40 This construction is omitted to avoid confusion.

45 High-pressure steam is taken from the steam space of the boiler through the pipes 16 and 16^a within the boiler and smoke-box, Fig. 2^a, and through a pipe 16^b extending outside of the boiler to the extreme end of the fire-box, and communicates with a pipe 16^c which has a universal joint connecting it with the cylinders 10. This joint accommodates itself to the movement of the rear 50 frame on the pivot 13 by which it is connected to the frame 2.

The exhaust steam from the high-pressure

cylinders passes through a pipe 17 which is connected by a ball-joint with the pipe leading 55 from the high-pressure cylinders and extends to, and communicates with, the inlet passages of the valve-chests of the intermediate cylinders 3.

The exhaust from the intermediate cylinders 3 passes through a pipe 18 which is connected to the exhaust pipes of the cylinders 3 by means of a ball-joint. The pipe 18 extends to and communicates with a pipe 19 which leads to the steam inlet ports of 60 the valve-chests of the low-pressure cylinders 20 carried by the forward frame 6. The exhausts from the cylinders 20 are coupled to the nozzle 21 through a pipe 22, having a 65 telescopic section which accommodates itself 70 to the movement of the frame 6 in respect to the boiler (see Fig. 2^a).

While I have shown in Fig. 1 each frame having four driving-wheels at each side 75 coupled to the piston of the respective cylinders, the number of driving wheels may be varied, according to the type of locomotive to which my invention is applied. By the above construction, a comparatively compact 80 triple expansion locomotive of the Mallet type is produced, in which the several frames are connected by articulated joints, and the length of the individual frames is no greater 85 than the length of the frames of an ordinary Mallet locomotive.

I claim:

1. The combination in a triple expansion locomotive of the Mallet type, of a rear frame of the locomotive; a boiler secured to 90 said frame; a forward frame connected by an articulated joint with the frame that supports the boiler, said boiler overhanging the said forward frame; low-pressure cylinders mounted on the forward frame; intermediate 95 cylinders mounted on the frame that supports the boiler; a tender frame pivotally connected to the rear frame of the locomotive; high-pressure cylinders located at the forward end of the tender frame; pipe connections between the boiler and the high-pressure cylinders, between the high-pressure cylinders and the intermediate cylinders, and between the intermediate cylinders and the low-pressure cylinders; and an exhaust pipe 100 connecting the low-pressure cylinders with 105 a nozzle in the smoke-box of the boiler.

2. The combination in a locomotive, of three frames; a boiler rigidly connected to and the low-pressure cylinders being coupled by ball-joints. 20
and supported by the intermediate frame and overhanging the forward frame; a tender
5 carried by the rear frame; low-pressure cylinders mounted on the forward frame; intermediate cylinders mounted on the intermediate frame; high-pressure cylinders mounted on the rear frame; a steam supply
10 pipe leading from the boiler to the valve-chests of the cylinders on the rear frame; pipes connecting the high pressure cylinders with the intermediate cylinders, and the intermediate cylinders with the low-pressure
15 cylinders, said frames being connected by articulated joints; and steam pipes between the high-pressure cylinders and the intermediate cylinders, the intermediate cylinders
25
30

3. The combination in a triple expansion locomotive, of three pivotally connected frames; a boiler rigidly secured to the central frame and overhanging the forward frame; high-pressure cylinders carried by the rear frame; intermediate cylinders carried by the frame that supports the boiler; low-pressure cylinders carried by the forward frame; a steam pipe connecting the boiler with the high-pressure cylinders; exhaust connections for the low-pressure cylinders; and pipes connecting the intermediate cylinders with the high and low pressure cylinders. 30

SAMUEL M. VAUCLAIN.
